UNITED STATES PATENT OFFICE.

SIMON COOPER, OF BROOKLYN, NEW YORK, ASSIGNOR TO VACUUM PULP PRODUCTS CORPORATION, OF NEW YORK, N. Y., A CORPORATION OF VIRGINIA.

MOLD AND PROCESS FOR FORMING ARTICLES FROM PULP OR OTHER PLASTIC MATERIAL.

Application filed August 22, 1917, Serial No. 187,541. Renewed December 29, 1923.

To all whom it may concern:

Be it known that I, SIMON COOPER, a citizen of the United States, residing at Brooklyn, in the county of Kings and State of New York, have invented certain new and useful Improvements in Molds and Processes for Forming Articles from Pulp or Other Plastic Material, of which the following is a specification.

10 My present invention relates particularly to the manufacture of hollow containers such as milk bottles and the like and aims primarily to enable the production of such articles in the requisite strength and durability from material of a pulp-like character.

15 A further and more specific object is to strengthen the bottom portions of such containers so that they will be fully capable of 20 withstanding the handling which such articles are ordinarily subjected to.

In the accomplishment of these objects I first preferably form a pulp wall or deposit by forcing the pulp material into a hollow porous mold of the desired shape while said mold is supported in one position and then produce a re-deposit or strengthening of certain portions of the pulp wall by turning the mold into a different position and further forcing material into the mold in this new position, either by actually forcing additional material into the mold or by applying additional pressure to that already within the mold. Usually the mold is first supported in an inverted position and then turned right side up for the purpose of reinforcing that part of the deposit which is to form the bottom of the completed article.

I have illustrated more or less diagrammatically in the accompanying drawing one form of apparatus for carrying out the invention, wherein Figure 1 is a front view of such apparatus, showing in dotted lines the first and final conditions of the suction chamber with the mold in inverted position; and Figure 2 is an enlarged sectional view of the suction chamber as in the second or intermediate step with the mold in upright position.

50 In the apparatus illustrated, atmospheric pressure is utilized as the force for filling the mold, this force being controlled by applying suction to the exterior of the mold while the interior of the mold is in com-

munication with a supply of pulp. Accordingly, the mold is inclosed within a suction chamber 3, connected by a pipe line 4 with a suction creating pump 5. A so-called "vacuum" tank is usually interposed in the suction line to eliminate pulsations of the 60 pump and provide for an even draw on the "vacuum" or suction chamber 3, and a separator 6 may also be placed in this line to prevent pulp passing back to the tank or to the pump.

65 The mold illustrated is for forming containers of the wide mouthed "milk bottle" variety and is shown made up of a correspondingly shaped gauze wall 7, and supported by ribbing 8, and a bottom 9, the 70 whole being formed suitably in sections to enable the removal of the completed article from within the mold. A hollow column or tube 10, serves as the support for the mold within the suction chamber and also as a 75 part of the means for supplying the pulp thereto, the mold being for the purpose detachably secured with its mouth over the open end of said supply tube. The balance of the pulp supply conduit is made up in the 80 illustration of a flexible tube 11 adapted to dip into the pulp reservoir 12.

A flexible connection 13 is also shown interposed in the suction conduit 4, these two flexible connections enabling reversal of the 85 suction chamber without breaking the connections thereto.

A main control valve 14 and a more finely regulatable valve 15 by-passed around said main control valve, are shown provided in 90 the suction line and a cut-off valve 16 may also be located in said line. Drain valves 17 may be provided at one or both ends of the suction chamber and a relief valve 18 is shown provided for admitting atmospheric 95 air through pipe 19 into the interior of the mold, said pipe terminating in a funnel-shaped nozzle 20 for admitting such air against the wall which forms the bottom of the molded product.

100 In practice, the pulp is usually first admitted with the mold in an inverted position like that shown in dotted lines in Figure 1, the pulp being admitted into the mold either gradually, as by the control of valve 15, 105 which may be a finely adjustable needle valve, or more suddenly, through the control of main control valve 14, the drain valves

17 and relief valve 18 being closed during such time. As the pulp rises in the mold a facing deposit is produced on the inner porous walls of the mold. Approximately 6 at the time that the mold becomes filled and the facing deposit is completed covering the entire interior of the mold, the suction chamber is reversed, end for end, and the mold thereby turned right side up, preferably 10 without interrupting the suction. A secondary deposit is thereby added to the first, without lamination, this second deposit being heaviest at the bottom portion of the container walls, due to the static head of 15 the liquid column in the mold. By regulating the degree of suction and controlling the reversing movement of the mold different effects may be obtained and the walls may be made heavier in certain parts than in 20 others, or walls of uniform strength may be produced. The results may be further varied by closing off the suction, before, during or after the reversing movement.

After a sufficient secondary deposit is obtained the mold is freed of surplus pulp, 25 usually by turning it back into the inverted first position and breaking the suction by opening relief 18. This gradually establishes an equilibrium of pressure on the 30 top and bottom of the pulp column, as the incoming air slowly passes through the deposited pulp, allowing the excess to drain slowly back into the reservoir. The admission of this relief air through funnel 35 20 directly beneath the bottom forming wall of the pulp deposit also provides an air cushion temporarily supporting this, the then uppermost part of the pulp deposit preventing the same from collapsing as 40 the support afforded by the pulp column is withdrawn. Then, after draining the suction chamber by way of valve 17, closing relief valve 18 and disconnecting pulp supply pipe 11 from the pulp reservoir, 45 suction is again applied to remove free moisture and to further compact and "felt" the deposited pulp. The molded product may then be removed from the mold for further treatment or simply be kept in the 50 mold for subsequent treatment. The suction chamber is preferably constituted so that it may be readily opened for the removal of the mold, as by making it in the form of a bell, as indicated, with jaw portions 55 21, clampingly engaged with the base part 22 by a slight rotary movement, after having been passed through notches 23 in the edge of such base.

It will be apparent from the foregoing 60 that the invention is suited to the production of articles of any desired shape and that such articles may be given the requisite strength to meet their particular uses.

I claim:

65 1. The process of forming articles from

pulp material which comprises forcing the material into the mouth of a hollow open-ended, porous mold while the mold is in an inverted position and then further forcing material into the mold with the mold positioned right side up. 70

2. The process of forming articles from pulp material which comprises forcing the material into a hollow porous mold while said mold is disposed in one set position 75 and then further forcing material into the mold while the same is disposed in a reverse set position.

3. The process of forming articles from pulp material which comprises filling a 80 hollow porous mold with the material while said mold is disposed in one set position and then turning the mold to reverse the same to another set position and further 85 forcing material into the mold. 85

4. The process of forming articles from pulp material which comprises applying suction to the exterior of a hollow porous mold whose interior is in communication with a body of pulp material while the 90 mold is in one set position then reversing the set position of said mold and again applying suction to the exterior of the same, to further force material into the mold.

5. The process of forming articles from 95 pulp material which comprises applying suction to the exterior of a hollow open-ended porous mold whose open end is in communication with a body of pulp material while said mold is disposed in an inverted position and reversing the position of said mold and applying suction to the exterior of the same while in said reversed position. 100

6. The process of forming articles from 105 pulp material which comprises applying suction to the exterior of a hollow open-ended porous mold whose open end is in communication with a body of pulp material while said mold is disposed in an inverted position, relieving the suction thereon, reversing the position of said mold, and again applying the suction while the mold is in such reversed position. 110

7. The process of forming articles from 115 pulp material which comprises applying suction to the exterior of an open-ended hollow porous mold whose open end is in communication with a body of the material while said mold is supported in an inverted position, and thereby producing a deposit on the inner porous walls of the mold, reversing the position of said mold end for end and applying suction to the exterior thereof while the interior is in communication with material, returning said mold to the first inverted position and then releasing the suction and freeing the mold of material in excess of the deposit made on the walls thereof. 120 125

8. The process of forming articles from 130

pulp material which comprises applying suction to the exterior of an open-ended hollow porous mold whose open end is in communication with a body of the material, while 5 said mold is supported in an inverted position and thereby producing a deposit on the inner porous walls of the mold, reversing the position of said mold end for end, and applying suction to the exterior thereof, returning said mold to the first inverted position and then releasing the suction and freeing the mold of material in excess of the deposit made on the walls thereof.

9. The process of forming articles from 15 pulp material which comprises applying suction to the exterior of an open-ended hollow porous mold whose open end is in communication with a body of the material while said mold is supported in an inverted position, and thereby producing a deposit on the inner porous walls of the mold, reversing the position of said mold end for end, returning said mold to the first inverted position and then releasing the suction and freeing the mold of material in excess of the deposit made on the walls thereof and then again applying suction after the mold has been disconnected from the supply of material.

20 25

10. The process of forming articles from

pulp material which comprises applying suction to the exterior of an open-ended hollow porous mold whose open end is in communication with a body of the material while said mold is supported in an inverted position, and thereby producing a deposit on the inner porous walls of the mold, reversing the position of said mold end for end, and applying suction to the exterior thereof while the interior is in communication with material, returning said mold to the first inverted position and then releasing the suction and freeing the mold of material in excess of the deposit made on the walls thereof 30 35 40

11. In the forming of pulp articles, suction means, a movable suction chamber flexibly connected therewith, a pulp reservoir, a porous mold in the suction chamber flexibly connected with the pulp reservoir, and a pulp separator interposed between the suction chamber and the suction means.

In testimony whereof I affix my signature.

SIMON COOPER.
